SHOE AND METHOD OF MAKING THE SAME

Ernst Schneider, Bad Kreuznach, Germany, assignor to Benjamin H. Stern, New York, N. Y.

Application July 14, 1933, Serial No. 680,349, and in Germany May 25, 1932

11 Claims. (Cl. 12—142)

This invention relates to the shoe art and deals more specifically with a pasted shoe, slipper, sandal, or the like.

It is an object of this invention to provide a new and improved attachment between the upper and the sole, which is both simple and cheap to effect, and which is highly efficient.

A further object of this invention is to provide a method of making shoes in which the upper 10 is cut substantially to the exact dimensions that it has in the finished product, thereby eliminating the step of trimming away surplusage of the upper after the lasting operation.

Further, it is an object of this invention to provide a shoe having a single outer sole, with no inner sole for lasting or the like, which shoe in all respects resembles a turned shoe, but which is much simpler and cheaper to construct.

And it is a further object of this invention to provide a sole so molded that the upper may be attached readily by cement, or sewing if desired, without the use of any machinery or lasts.

Another object of this invention is to provide a shoe which is so simple and cheap to construct, 25 that the separate elements may be bought by a prospective user, and assembled as a home made finished product.

And finally it is an object of this invention to provide a molded sole shoe which is very flexible, 30 simple in structure, and highly ornamental.

These and other objects of the invention will be apparent to those skilled in the art from the following description taken in connection with the accompanying drawing, in which

35 Fig. 1 is a side elevation of a shoe constructed in accordance with the principles of this invention.

Fig. 2 is a perspective view with the shoe cut away along the lines 2—2 of Fig. 1.

40 Fig. 3 is a sectional view taken along the lines 3—3 of Fig. 1.

Referring in detail to the drawing the shoe 10 comprises an outsole 11 molded with an upturned flange 12 running peripherally around the sole. 45 This is accomplished with any suitable sole molding machine while the leather is in temper. The sole is marginally reduced at 13, providing a shoulder 14. The reduced portion has a width from 17 to 18 (Figs. 1 and 2) from the ball line 50 on one side forwardly around to the ball line on the other side; rearwardly from the ball line the reduced portion is gradually made wider until at the breast (15—16) of the heel the reduced portion extends down to the heel seat, that is from 55 18 to 19. In forming the reduced portion suffi-

cient stock is removed to correspond to the thickness of the upper 20, the edge of which abuts against the shoulder 14. The upper is cemented against the vertical wall of the reduced portion 13. Rubber cement, latex, or a celluloid cement may be used for this purpose.

The upper 20 made up of the vamp and quarters in the usual way is cut to the correct dimensions so that it may be cemented to the reduced portion of the sole and give the finished

60 shoe, without further trimming. A lining 30 prepared in the usual way, is sewed to the upper 20 along the top marginal edge 21, said lining at its lower extremity being free from the upper. When

65 the upper is attached to one face of the reduced portion 13, the lining 30 contacts with the other face of the reduced portion, and the marginal extension of the lining is turned inwardly and is

70 laid flat on the upper surface of the outsole, inside the shoe. The reduced portion 13 now lies disposed between the upper 20 and the lining 30. A counter 40 is cemented in place in the heel portion of the shoe, between the lining 30 and the reduced portion 13, the counter being shaped

75 to give support to the rear of the upper in a manner well understood in the art. A shank piece 41 of relatively stiff leather, with or without a shank stiffener is placed over the inturned edge of the upper and nailed or otherwise attached to the heel 50. This shank piece is used for the

80 usual purpose in shoe making, namely to give rigidity to the shoe backwardly from the ball line. If desired the lining 30 may be cemented down against the outsole, although this is not necessary in certain cases. A sock lining or insole 33 is now placed in the shoe over the shank piece and covering the inturned edge of the lining,

85 thus completing the shoe. Obviously any suitable ornamentation may be applied to the upper, or indeed the upper may be constructed in accordance with any suitable style.

Following the assembly of the parts, as described above, a last may be inserted into the shoe and the same beaten or hammered out to conform more accurately to the desired shape.

It is contemplated that in view of the simplicity of the structure of this shoe, and further in view of the ease of assembling the same, that the parts be brought on the market where they may be bought by a prospective wearer and assembled at home.

Obviously many changes in the herein disclosed specific embodiment will readily suggest themselves to those skilled in the art. For example, it is within the scope of this invention to

substitute stitching for the cementing in attaching the upper to the sole. Also, the particular shape of the upturned flange 12 may be varied, as well as the shape of the reduced portion 13, 5 to give various style effects.

This invention is therefore not to be limited, except as defined in the appended claims.

Having thus described my invention I desire to claim and secure by Letters Patent:

- 10 1. The method of making shoes which comprises in combination the steps of supplying an outsole having an upstanding flange, supplying an upper and a lining joined together, attaching said upper to said flange, turning in the edge of said lining, inserting an insole, and completing the shoe.
- 20 2. The method of making shoes which comprises in combination the steps of supplying an outsole having an upstanding flange, supplying an upper and a lining joined together, cementing said upper to said flange, turning in the edge of said lining, inserting an insole, and completing the shoe.
- 25 3. The method of making shoes which comprises in combination the steps of supplying an outsole having an upstanding flange provided with a reduced portion, supplying an upper and a lining joined together, attaching said upper to said reduced portion, turning in the edge of said lining, inserting an insole, and completing the shoe.
- 30 4. The method of making shoes which comprises in combination the steps of supplying an outsole having an upstanding flange provided with a reduced portion, supplying an upper and a lining joined together, cementing said upper to said reduced portion, turning in the edge of said lining, inserting an insole, and completing the shoe.
- 40 5. The method of making shoes which comprises in combination the steps of supplying an outsole having an upstanding flange, supplying an upper having substantially the same dimensions as the same is to have in the finished shoe and having a lining attached to its top marginal edge, cementing the bottom marginal edge of said upper to said flange, turning the bottom edge of said lining on to the top surface of the said outsole, inserting a shank piece and an insole, and finishing the shoe.
- 50 6. A shoe of the class described comprising in combination, an outsole having an upturned marginal flange, an upper having a bottom marginal edge, said edge being cemented to said flange, a lining attached to said upper and having a bottom marginal edge, a portion of said last mentioned edge being disposed upon the upper surface of said outsole, said flange being disposed between the upper and the lining, and an insole covering said lining upon the surface of said outsole.

7. A shoe of the class described comprising in combination, an outsole having an upturned marginal flange having a reduced portion, an upper having a bottom marginal edge, said edge being cemented to said reduced portion, a lining attached to said upper and having a bottom marginal edge, a portion of said last mentioned edge being disposed upon the upper surface of said outsole, said flange being disposed between the upper and the lining, and an insole covering said lining upon the surface of said outsole.

8. A shoe of the class described comprising in combination, an outsole having an upturned marginal flange, an upper having a bottom marginal edge, said edge being cemented to said flange, a lining attached to said upper and having a bottom marginal edge, a portion of said last mentioned edge being disposed upon the upper surface of said outsole, said flange being disposed between the upper and the lining, a shank piece, and an insole covering said portion of the lining which lies on the surface of the outsole.

9. A shoe of the class described comprising in combination, an outsole having an upturned marginal flange provided with a reduced portion, an upper having a bottom marginal edge, said edge being cemented to said reduced portion, a lining attached to said upper and having a bottom marginal edge, a portion of said last mentioned edge being disposed upon the upper surface of said outsole, said flange being disposed between the upper and the lining, a shank piece, and an insole covering said portion of the lining which lies on the surface of the outsole.

10. A shoe of the class described comprising in combination, an outsole molded to form an upturned flange having a reduced portion forming a shoulder, an upper having a top and a bottom marginal edge, a lining attached to said upper along the top edge thereof, the bottom edge of said upper being cemented to said reduced portion and abutting said shoulder, the bottom edge of said lining being turned over on to the top surface of the outsole, and an insole disposed over said last mentioned edge.

11. A shoe of the class described comprising in combination a sole having a heel portion and a forward portion, said sole being provided with an upstanding flange having a reduced portion, said reduced portion on the forward part of the sole extending from the top of said flange down to a line spaced from the tread surface of the sole and said reduced portion at the said heel portion extending from the top of said flange down to the heel seat line, an upper having a bottom marginal edge, said edge being attached to said reduced portion, and a heel attached to said heel seat.
